UNITED STATES PATENT OFFICE.

WILLIAM DURHAM SARGENT, OF NEW YORK, N. Y., ASSIGNOR TO AMERICAN BRAKE SHOE & FOUNDRY COMPANY, OF NEW YORK, N. Y., A CORPORATION OF NEW JERSEY.

METHOD OF MAKING BRAKE-SHOES.

SPECIFICATION forming part of Letters Patent No. 739,791, dated September 22, 1903.
Application filed February 13, 1903. Serial No. 143,218. (No model.)

To all whom it may concern:

Be it known that I, WILLIAM DURHAM SARGENT, a citizen of the United States, residing in the city and State of New York, have invented a certain new and useful Method of Making Brake-Shoes, of which the following is a specification.

My invention relates to the manufacture of brake-blocks or the wearing-soles of brakes, such as in common use on railway-cars, and especially to that style of shoe in which there is an insert of different metal designed to be exposed by wear and to improve the wearing qualities and durability of the shoe. A brake-shoe of this general type is illustrated in my former United States patent, No. 516,992, in which there is a plug or insert of metal of a greater degree of hardness than that of the main body of the shoe and which is made by casting the body of the shoe of softer metal with recesses and then pouring in the hard metal for the insert-blocks. In my later United States patent, No. 587,493, I have illustrated a method of making inserts of malleable "expanded" metal, which is cast in the shoe and has been found to very much improve the frictional resistance of the shoe.

The principal object of the present invention is to improve upon the structure of brake-shoes by combining both the qualities of the above-mentioned methods, securing the durability due to the hardened insert, and the increased friction due to the malleable metal embedded in the shoe.

A further object of the invention is to provide for the manufacture of a uniform quality of briquets or inserts and provide a convenient means for preserving the malleable metal from rust and to render easy the proper proportioning of the two metals and the proper placing of the malleable metal in the cast metal.

A further object is to provide a process by which the briquets or inserts may be conveniently made at central distributing-stations and may be cheaply stored and packed and transported to the foundries where they are to be used in making of the complete shoe.

I attain the above objects, as well as other

advantages which will hereinafter appear, by means of the mode of manipulation described below, and illustrated in a preferred form in the accompanying drawings.

Figure 1 represents a perspective view and partial section of an iron mold used for casting the briquets. Fig. 2 is a partial section illustrating the mode of placing the expanded metal in the briquet-molds. Fig. 3 illustrates a fragment of the form of malleable iron or steel which I prefer to use. Fig. 4 is a perspective view of the finished briquet. Fig. 5 is a plan view of the common brake-shoe mold, showing the briquets in position therein ready to have the softer cast metal poured in. Fig. 6 is a perspective and central section of a complete brake-shoe, showing the briquets or inserts therein and the malleable metal embedded in the briquets in section.

As the result of a long series of experiments the trade has come to recognize it as important to have the wearing-surface of a brake-shoe of varying degrees of hardness, and both hardened inserts and a series of embedded malleable filaments, such as expanded metal webbing, have come into very general use.

There are objections to the process of making brake-shoes by casting metal about a series of layers of expanded metal in the mold partly because this is not economical in the use of expanded metal and it prevents the use of hardened inserts in the body of the softer cast metal, and, further, it is found to be difficult to preserve the expanded metal from rust between the time of its manufacture and its actual use in making a shoe. On the other hand, the method of using hardened blocks has some disadvantages because the chill of the surface around them produces a harsh action upon the wheels and because the hardened metal alone decreases the frictional resistance of the brake.

In order to overcome many of these difficulties and others, I proceed as follows: I provide an iron mold *a*, having a series of nests or depressions *b* cut therein, of a proper shape, and in these I place the proper quan-

ity of expanded metal *e*, placing the same so that the strands of different layers will alternate in longitudinal position, as shown in Fig. 2. These may be crowded irregularly 5 into the mold, and since it is not necessary to cover the edges with cast metal there is no necessity for accurate cutting of the pieces to fit in the mold. Upon the top of the mold-block *a* I then place a convenient cover, such 10 as the iron plate *c*, which is provided with a series of inlet-apertures *d*, and thereupon pour in the metal to embed the expanded metal therein and form the briquet *f*. (Shown in Fig. 4.) The contact of the cast metal 15 with the iron mold chills the surface of the cast metal of the briquet, and this hardness is very useful to preserve the briquets from rust when they are stored in quantities. It is evident that both the relative quantities 20 of malleable iron and of cast-iron and the quality of the cast-iron may be regulated at will and may be rendered perfectly uniform. The briquets *f*, which are the first or 25 partial product of my process, may then be shipped to the point where it is desired to use them in the making of brake-shoes, and the subsequent step of the process may be carried out in any ordinary foundry with the ordinary apparatus. In carrying out the 30 second step of placing the briquets in the shoe itself I may use any common form of sand mold, such as shown in Fig. 5, and the briquets being placed in proper position therein the softer cast-iron to form the body 35 of the shoe is poured in, as will be readily understood. Upon contact with the molten metal the hardened surface of the briquets will be annealed, which will avoid the harsh action on the wheels which might otherwise 40 result, and a good joint is secured between the two qualities of metal. In order to insure the proper retention of the briquets in place, I prefer to make them of a truncated-pyramid form. (Shown in Fig. 4.) 45 It will be evident that by this process I attain the greatest possible economy in the use of the expanded metal and make it easy to secure a perfectly-uniform quality of insert. At the same time the exact composition of 50 the hard cast metal is under complete control. It is also very important that the expanded metal may be used up in making the briquets in quantities and so stored and packed as to prevent deterioration by rust. 55 It is easy to insert the proper quantity of malleable metal in the iron mold, and this renders accurate cutting of sheets of expanded metal or folding of the same unnecessary. Also the quality of the hard metal forming 60 the briquet is less affected in this form by the molten iron used in making the complete shoe, the malleable metal is better protected, and is embedded in a more solid and more durable and suitable medium than when directly cast into the shoe. The advantages of 65 having these cast inserts made at a central distributing-point of uniform character and

under complete control of an expert and the advantages in packing and transportation will readily occur to those familiar with the art. Since the total weight of the inserts will ordinarily be something like fifteen per cent. of the weight of the brake-block itself, it is also apparent that a great saving in the cost of transportation may be made, since the briquets may be used in any foundry by the simplest methods in forming the complete shoe. The peculiar mixture of the three grades of metal, as above described, attains the highest degree of durability combined with the best quality of friction-surface, and consequently the brake-shoes may be made of a uniform and an excellent quality without the necessity of employing expert labor in the casting of the final shoe. 85

While I have illustrated the particular form of the malleable metal which I prefer to use as the resistance-filaments in the shoe, it will of course be understood that any other form of metal—such as wire, scrap cuttings, or any other form of filaments—may be used indifferently, and while I generally find it advantageous for the reason stated to use an iron mold for the briquets and a sand mold in making the shoe this is of course not essential to my invention, and when the briquets are not desired to have a chilled surface any other suitable mold may be used. 95

Having thus described my invention, what I claim, and desire to secure by Letters Patent, is the following:

1. The process of making brake-shoes which consists in forming briquets or insert-blocks of cast metal containing filaments of malleable metal, and afterward placing said briquets or blocks in a mold and embedding the same by casting around them the metal to form the body of the shoe. 105

2. The process of making brake-shoes which consists in providing a metal mold, placing therein a quantity of malleable metal, pouring in a quantity of hard cast metal to form a briquet, and thereupon placing a series of said briquets in a brake-shoe mold and embedding the same in a body of softer cast metal, 115 substantially as described.

3. The process of making brake-shoes which consists in providing a briquet or insert composed of hard cast metal cast around a quantity of malleable metal, placing a series of 120 said briquets in a mold and casting softer metal therein to embed the said blocks, substantially as described.

4. The process of making brake-shoes which consists in providing an open metal mold of standard form and size, placing therein a quantity of expanded metal and casting thereon a quantity of hard iron to form a briquet, thereupon providing a brake-shoe sand mold, placing a series of said briquets therein, and pouring in soft cast-iron to embed the said briquets in the body of the shoe, substantially as described. 125 130

5. A brake-shoe comprising a body of soft

cast metal having embedded therein briquets of harder cast metal, said briquets containing a quantity of malleable metal.

6. A brake-shoe comprising a series of filaments of malleable metal embedded in blocks of hard cast metal, and said blocks being embedded in soft cast metal forming the body of the shoe.

7. A soft-cast-metal brake-shoe containing embedded blocks of hard cast metal, said blocks themselves containing a framework of malleable metal, and the surfaces of said blocks being annealed as the soft metal is poured around them, substantially as described.

8. A brake-shoe briquet-insert consisting of a cast-metal block of truncated-pyramid form having embedded therein in the casting an approximately uniformly distributed series of filaments of malleable metal extending entirely through the block, substantially as and for the purpose described.

In testimony whereof I have hereunto signed my name in the presence of the subscribing witnesses.

WILLIAM DURHAM SARGENT.
